6 Claims. (Cl. 340—221)

This invention relates to an alarm device for the objects of control such as temperature and pressure of each part of various mechanisms, for example, a generator, a liquid level of a tank and the like, more particularly to an alarm device which directly informs the content of an alarm by means of words or a voice, other than an alarm device heretofore employed which indirectly informs the content of an alarm by means of a bell, buzzer, siren, gong or the like.

If the objects of control such as temperature and pressure of, for example, a generator or a liquid level of a tank is not held at a prescribed value during normal operation, a desired performance of its whole system cannot be expected. Furthermore, the function of its entire system is sometimes lost even by a change of one of the objects of control. Therefore, the value of the objects of control is always measured and when the value varies due to some causes the variation is immediately informed so as to remove the cause. Hitherto, alarm devices have been used which raise an alarm by means of a bell, buzzer, siren, gong or the like merely according to accidents. However, it is relatively difficult in a system having many objects of control to detect what or which point is out of order, so that a delay in detection of the wrong point is occasioned and bad influences are often exerted upon the entire system. The prior art devices inevitably possess such disadvantages. In addition, even if the wrong point is found in this case, it is impossible to know what the trouble really is. That is, the alarm device merely informs that the object of control is out of order and an operator cannot promptly judge what step must be taken to remove the cause of the trouble, unless he is skilled in the art. Furthermore, even when two or more of the objects of control are out of order simultaneously owing to some trouble at a point other than the objects of control, the conventional alarm device only informs the trouble of the objects of control without informing the cause of such trouble. Therefore, only a highly skilled person can find the real cause of the trouble. In such a case, if the content of the trouble is informed by means of an aural message, an operator who is not very skilled in the art can take a suitable step to remove the trouble.

Accordingly, a primary object of this invention is to provide an alarm device which informs directly by means of an aural message the content of a trouble in the object of control and a counterplan to remove the trouble.

Another object of this invention is to provide an alarm device which informs directly by means of an aural message the content of troubles caused simultaneously in a plurality of the objects of control, the cause common to them and a counterplan to remove the cause.

Other objects, features and advantages of this invention will become apparent from the following description taken in conjunction with the accompanying drawings, in which:

FIGURE 1 is a systematic connection diagram illustrating an example of an alarm device for the object of control according to this invention; and

FIGURES 2 to 4, inclusive, are also systematic con-

2

nnection diagrams respectively illustrating other examples of this invention.

FIGURE 1, A₁, A₂, . . . A_n respectively indicate the objects of control, with which signal generators S₁, S₂, . . . S_n are associated, which respectively operate when the objects are out of order. Each of these signal generators S₁, S₂, . . . S_n may be formed to have contact structure connected to a power source and it closes when a trouble occurs in the object of control, by which a step voltage is led out through the contact. In this case, the contact may operate as a contact of, for example, a temperature or pressure switch. In the figure, a power source E is connected through a contact a to a load L and its both ends are utilized as output ends. The contact a is so designed as to close due to a trouble of the object of control and a step voltage is obtained at the both ends of the load L. Associated with the signal generators S₁, S₂, . . . S_n are memory circuits M₁, M₂, . . . M_n. These memory circuits have a switching function of a relay circuit or the like including, for example, a flip-flop circuit or a differentiation circuit and they are actuated by the output respectively from the signal generators S₁, S₂, . . . S_n and have a memory function that they hold their actuation. In the figure, the memory circuit consists of a differentiation circuit U including a capacitor C and a resistor R connected to the output end of the signal generator, a relay coil L₁, a pair of its movable contacts b₀ and c₀ and a pair of normally closed fixed contacts b₁ and c₁ and a pair of normally open contacts b₂ and c₂. The output end of the differentiation circuit U is connected to the relay coil L₁ through the contacts b₁ and b₀. The contacts b₂ and c₂ are connected respectively to the positive and negative power sources +B and -B, and output terminals are led out from the contacts b₀ and c₀.

To the memory circuits M₁, M₂, . . . M_n is connected an instructor T in common to them. When one of the memory circuit M₁, M₂, . . . M_n has made a memory, the instructor T detects the circuit and generates a signal to select an aural information source corresponding to the circuit having made a memory. In FIGURE 1, the instructor T is composed of diodes D₁, D₂, . . . D_n respectively connected to the contacts c₀, namely each one of the output terminals of the memory circuits M₁, M₂, . . . M_n, an amplifier AM₁ connected in common to these diodes, a relay coil L₂ actuating a pair of contacts d₀ and e₀ connected to a positive power source +B, and an amplifier AM₂ for getting the amplifier AM₁ out of operation and energizing the relay coil L₂. There are provided terminals connected respectively to the amplifier AM₁, the contacts d₀ and e₀ and the input side of the amplifier AM₂. A switching circuit SW₁ is connected in common to the memory circuits M₁, M₂, . . . M_n. By the command of the instructor T, the switching circuit SW₁ operates to select and change-over one of the memory circuits M₁, M₂, . . . M_n. As is illustrated in the figure, the switching circuit SW₁ may be of a rotary contact structure which consists of fixed contacts f₁₁, f₁₂, f₁₃, . . . f_{1n} respectively connected to the contacts b₀ namely the output terminals of the memory M₁, M₂, . . . M_n, a rotary movable contact f₁₀ and a relay coil L₃ formed to change-over the movable contact f₁₀ step by step in a sequential order. The relay coil L₃ is connected to the output terminal of the amplifier AM₁ of the instructor T and the movable contact f₁₀ is connected to the input terminal of the amplifier AM₂ of the instructor T.

Furthermore, another switching circuit SW₂ is connected in common to the memory circuits M₁, M₂, . . . M_n. The switching circuit SW₂ interlocks or gangs with the aforementioned switching circuit SW₁ and operates to reset a memory circuit having made a memory in re-

spose to a signal from a reset and memory switch circuit described later. This switching circuit SW_2 may be formed in exactly the same manner as the aforementioned switching circuit SW_1 , so that parts corresponding to those of the switching circuit SW_1 are marked with the same numerical reference f but with suffixes such as 20, 21, 22 . . . 2n. The other terminals of the memory circuits $M_1, M_2, \dots, M_n$, namely the contacts b_0 are connected respectively to the fixed contacts $f_{21}, f_{22}, f_{23} \dots f_{2n}$ and a terminal is connected to the movable contact f_{20} .

Furthermore, aural information sources $B_1, B_2, \dots, B_n$ are provided which correspond to the objects of control $A_1, A_2, \dots, A_n$. When some of the objects of control have got out of order, aural informations of the content of the trouble and a method for removing it are obtained from the aural information sources. These aural information sources may be composed of magnetic tapes $P_1, P_2, \dots, P_n$ having, for example, the above aural informations recorded thereon and magnetic heads $H_1, H_2, \dots, H_n$ respectively corresponding to the magnetic tapes. These magnetic tapes may be driven respectively, for instance in an endless manner. To give the tapes in an endless manner, the magnetic tapes are so designed as to be driven by capstan CP in common to them in the figure. MT is a motor for driving the capstan. To the aural information sources $B_1, B_2, \dots, B_n$ is connected a switching circuit SW_3 in common to them, by which one of the aural information sources is selected. This switching circuit SW_3 may be formed in the same manner as the switching circuits SW_1 and SW_2 and the circuit SW_3 is ganged with them. Accordingly, the switching circuit SW_3 selects an aural information source which corresponds to a memory circuit chosen by the switching circuit SW_1 due to a command of the instructor T. In FIGURE 1, parts of the switching circuit SW_3 corresponding to those of the circuit SW_1 are marked with the same numeral reference f but with suffixes such as 30, 31, 32, . . . 3n. At the next stage of the switching circuit SW_3 , its movable contact f_{30} is connected to a voice or audio frequency amplifier AM_3 , to which a speaker SP is connected. In this case, a power source circuit for the amplifier AM_3 is so designed as to close for the first time when the instructor T detects the operation of the memory circuit, by which power may not be unnecessarily consumed by the amplifier AM_3 . To this end, the terminal of the instructor T, namely the contact d_0 is connected to the power source circuit of the amplifier AM .

A cam contact mechanism F is provided which is associated with the capstan CP or the motor MT and the mechanism F is formed in such a manner that contacts are closed at positions corresponding to the start and end of the records on the respective magnetic tapes. In the figure two contacts g_0 and h_0 are provided. This cam mechanism F is connected to a memory and reset-switch circuit RS. As is illustrated in FIGURE 1, the memory and reset-switch circuit RS consists of a relay coil L_4 having one end thereof connected to both ends of the grounded contact g_0 , a memory contact i_0 and a reset contact j_0 , the contact i_0 being inserted between the contact h_0 having one end thereof grounded and the movable contact f_{20} of the switching circuit SW_2 . A confirmation circuit K which may preferably have a push-button contact k_0 is provided, and its contact k_0 is inserted between one end of the relay coil L_4 and the positive side $+B$ of a power source. Furthermore, the contact j_0 is also inserted between one end of the relay coil and the positive side $+B$ of the source. The motor MT is connected to the power source through the contact d_0 of the instructor T.

With such an arrangement as described above, when one of a plurality of the objects of control gets out of order an operator can learn from the speaker SP the content of the trouble and a counterplan thereto. That is, if the objects of control, for example, A_1 gets out of order, the contact a of the signal generator S_1 closes and

a step voltage is produced across the both ends of the load L. This step voltage is differentiated by the differentiation circuit U at its rising time and the differentiated output is supplied to the relay coil L_1 through the contacts b_1 and b_0 to change-over the contacts b_0 and c_0 to the fixed contacts b_2 and c_2 . Thus, the relay coil L_1 is connected to the power source $+B$ and held by itself and the memory circuit M_1 makes a memory that the object of control A_1 is out of order.

On the other hand, since the diode D_1 of the instructor T is connected to the power source $-B$ through the contacts c_0 and c_2 , the diode D_1 becomes conductive and accordingly the amplifier AM_1 also becomes conductive, whereby an output of a certain level is obtained from the output of the amplifier AM_1 and the output is supplied to the relay coil L_3 . In response to this, the movable contact f_{10} of the relay coil L_3 selects the fixed contacts $f_{11}, f_{12}, \dots, f_{1n}$ at every step. When the contact f_{10} has reached the fixed contact f_{11} , the contact f_{11} is connected to the power source $-B$ through the contacts c_0 and c_2 and the amplifier AM_2 acts to obtain an output of a certain level. Then, the output is supplied to the relay coil L_2 , thereby to close its contacts d_0 and e_0 . Accordingly, as soon as the motor begins to operate, the amplifier AM_3 becomes actuated. At this time, the operation of the amplifier AM_1 is turned "off" by the output of the amplifier AM_2 . The contact f_{10} is in contact with the contact f_{11} and the contacts f_{20} and f_{30} of the switching circuits SW_2 and SW_3 interlocking with the switching circuit SW_1 are connected respectively to the contacts f_{21} and f_{31} , thereby selecting the memory circuit M_1 and the magnetic head H_1 of the aural information source B_1 . Accordingly, a signal from the aural information source B_1 is suitably amplified by the amplifier AM_3 through the switching circuit SW_3 and the speaker SP informs an occurrence of the trouble in the object A_1 together with its content and a counterplan therefor. The content of the aural information source B_1 is repeatedly broadcast due to endless driving of the magnetic tape P_1 , but the contacts g_0 and h_0 of the cam mechanism F are closed, for example, at every broadcasting. When the operator knows the trouble and its content, he will immediately be able to close the confirmation contact k_0 .

In such a case, since the relay coil L_4 is connected to the power source $+B$ through the contact k_0 , the relay coil L_4 is energized to close its contact i_0 , by which the relay coil L_4 is in selfhold and the contact j_0 also closes. When the contacts g_0 and h_0 close, the ground of the contact h_0 is connected to the relay coil L_1 of the memory circuit M_1 through the reset contact i_0 and the contacts f_{20} and f_{21} of the switching circuit SW_2 . Accordingly, the contacts b_0 and c_0 of the relay coil L_1 are reset and the contacts d_0 and e_0 of the relay coil L_2 are also reset, putting the amplifier AM_3 out of operation and stopping the motor MT. At the same time, the ground of the contact g_0 is connected to the relay coil L_4 , by which its contacts j_0 and i_0 are reset.

FIGURE 2 illustrates another example of this invention. In this example, each of aural information sources $B_1, B_2, \dots, B_n$, which are the same as illustrated in FIGURE 1, comprises independently a capstan CP and a motor MT and is formed to be of a cartridge type, including a magnetic tape and a magnetic head. The aural information sources are respectively provided with cam contact mechanisms $F_1, F_2, \dots, F_n$ and these sources are the same as those in FIGURE 1 except that contacts h_0 of the cam contact mechanisms are connected together and connected to a contact i_0 of a memory reset switch circuit RS and that contacts g_0 are similarly connected together and connected to a contact j_0 . The operation of the device above mentioned will be easily understood from that of the device shown in FIGURE 1. For the sake of brevity, no further explanation will be made in this specification.

FIGURE 3 illustrates another example of this invention, in which when two or more of a plurality of objects

of control have got out of order simultaneously the content of the troubles common to them are to be informed. To perform this, another memory circuit M_m is provided in addition to memory circuits $M_1, M_2, \dots, M_n$ and fixed contacts f_{1m}, f_{2m} and f_{3m} are provided in switching circuits SW_1, SW_2 and SW_3 respectively. Furthermore, another diode D_m is provided in the group of diodes of an instructor T and their connections are the same as in FIGURE 1. On the other hand, the output ends of two memory circuits, for example, M_2 and M_3 corresponding to the objects of control A_2 and A_3 relative to each other, namely contacts, for example, b_0 are connected to a load circuit R_m respectively through diodes D_{2m} and D_{3m} and their output ends are connected to the input end of the memory circuit M_m . Thus, the content of an alarm due to the relationship between the objects of control A_2 and A_3 can be informed, as is apparent from the foregoing made in connection with FIGURE 1.

FIGURE 4 illustrates another example of this invention, in which an alarm is raised due to the relationship which is the same as in FIGURE 3. Also in this example, a memory circuit M_m , an aural information source B_m and contacts f_{1m}, f_{2m} and f_{3m} of switching circuits SW_1, SW_2 and SW_3 are provided. Output ends of signal generators relative to each other are connected to a load circuit L_m respectively through diodes D_{2m} and D_{3m} and their output ends are connected to an amplifier AM_m . Then, the output end of the amplifier AM_m is connected through contacts $1m_1$ and $1m_0$ to relay coil L_m having a pair of movable contacts $1m_0$ and mm_0 , fixed contacts $1m_1$ and $1m_2$ to the contact $1m_0$ and fixed contacts mm_1 and mm_2 to the contact mm_0 . The contacts $1m_2$ and mm_2 are connected to the power source $+B$ and the contact mm_0 is connected to the input end of the memory circuit M_m . Since other components are the same as in FIGURES 1 and 3, their explanation will be omitted. In this case, however, it is necessary that the contact f_{2m} of the switching circuit SW_2 is connected to the relay coil L_m , thereby applying ground to the coil to reset it when resetting.

It will be apparent that many modifications and variations may be effected without departing from the scope of the novel concept of this invention.

What is claimed is:

1. An alarm device announcing a message upon the occurrence of a condition in each of a plurality of systems, comprising

- (a) a plurality of transducers each corresponding to and associated with a respective system and each including a control signal generator generating an output signal upon the occurrence of the condition,
- (b) first memory circuits each connected to and responsive to an output of a respective signal generator,
- (c) control means connected to each of said first memory circuits and responsive to an output of any one of said first memory circuits for producing a switching signal,
- (d) means responsive to said switching signal for selectively connecting each of said first memory circuits to said control means to disable said switching signal upon connection of the respective memory circuit which has an output corresponding to the occurrence of the associated condition,
- (e) aural information sources each respectively corresponding to a respective one of the plurality of conditions,
- (f) an aural message generating device connected to said sources for broadcasting information from said sources,
- (g) a first switching circuit responsive to said switching signal for selectively connecting each of said aural information sources to said generating device in synchronism with the selective connection of said

5

6

memory circuits to said control means by said connecting means, and

(h) a reset circuit connected to each of said first memory circuits for returning the device to its initial position.

2. An alarm device as defined in claim 1 wherein each of said signal generators includes a power source, a load, and a switch responsive to the occurrence of a condition connected between said power source and said load.

3. An alarm device as defined in claim 1 wherein each of said first memory circuits includes a differentiation circuit connected to an output of a respective one of said signal generators, a relay connected to said differentiation circuit, and a voltage source, said relay including a self holding contact disposed for connection to said voltage source in response to the output signal from a respective one of said signal generators and disposed for disconnection from said voltage source in response to an output of said reset circuit and contact means for delivering said output signal to said control means.

4. An alarm device as defined in claim 1 wherein said control means includes a plurality of diodes each connected to an output of a respective one of said first memory circuits, a first amplifier having an input connected in common to said diodes, an output of said first amplifier being connected to said connecting means and to said first switching circuit for actuation of each, and a second amplifier having an output connected to the input of said first amplifier and deactivating said first amplifier in response thereto, the output of said second amplifier being connected to said aural information sources, said connecting means being connected between an input of said second amplifier and each of said first memory circuits.

5. An alarm device as defined in claim 1 further comprising a second memory circuit connected to outputs of a respective pair of first memory circuits and responsive to a coincidence of the respective outputs of said pair for producing a corresponding output therefrom, said control means being connected to said second memory circuit and responsive to an output therefrom to produce said switching signal, said connecting means being further responsive to said switching signal for further selectively connecting said second memory circuit to said control means to disable said switching signal upon connection of said second memory circuit.

6. An alarm device as defined in claim 1 further comprising a second memory circuit connected to outputs of a respective pair of said transducers and responsive to a coincidence of the respective outputs of said pair for producing a corresponding output therefrom, said control means being connected to said second memory circuit and responsive to an output therefrom to produce said switching signal, said connecting means being further responsive to said switching signal for further selectively connecting said second memory circuit to said control means to disable said switching signal upon connection of said second memory circuit.
